UNITED STATES PATENT OFFICE

2,493,542

ELECTRIC HEATING UNIT

Max McGraw, Chicago, Ill., assignor to McGraw
Electric Company, Elgin, Ill., a corporation of
Delaware

Application July 29, 1947, Serial No. 764,487

3 Claims. (Cl. 201—73)

1

My invention relates to electric heating units and particularly to means for supporting the resistor in such units.

An object of my invention is to provide an electric heating unit comprising very thin sheets of electric insulating material backed by metal sheets, the metal sheets having an electric-insulating coating thereon.

Another object of my invention is to provide an electric heater comprising a very thin sheet or sheets of mica unable to support the resistor by themselves, backed up by a metal sheet or sheets having on their entire outer surfaces an electric-insulating coating, the area of said metal sheets being substantially the same as that of the mica sheets.

Other objects of my invention will either be apparent from a description of several forms of electric heaters embodying my invention or will be pointed out in the course of such description and be set forth in the appended claims.

In the drawings.

Figure 1 is a view, in front elevation, of an electric heater embodying my invention,

Fig. 2 is a view in section therethrough, taken on the line 2—2 of Fig. 1,

Fig. 3 is a sectional view of a modification embodying my invention,

Fig. 4 is a sectional view of a still further modification of electric heater embodying my invention, and,

Fig. 5 is a fragmentary view taken on the line 5—5 of Fig. 1.

Referring first of all to Figs. 1 and 2, I have there shown an electric heating unit, designated in its entirety by the numeral 11, which heating unit comprises two halves or parts 13 and 15. Each of the parts 13 and 15 comprises a relatively very thin sheet 17 of mica or other electric-insulating material, which sheet may be of any desired contour and dimensions and is here shown as substantially rectangular in outline. The thickness of the mica sheet 17 is on the order of .003" and while I have mentioned a particular thickness I do not desire to be limited thereto but may make the thickness of the mica sheets 17 of any desired value ranging from .0025" to .0035".

I further provide a relatively thin metal sheet 19, which metal sheet may be of substantially the same contour and have substantially the same overall dimensions as those of the mica sheet. Preferably I use a thin aluminum sheet, the thickness of which is on the order of .035" with a range of from .03" to .04".

2

I provide at each side of the units 13 and 15 a relatively thick strip 21 of mica or of other electric-insulating material, having a thickness of about .035", which strip is provided with recesses 23 in its outer edge, which outer edge overhangs the outer edge of strips 17 and 19. The strips 21 are held in the desired and proper operative position by small rivets 25 extending through not only the strip 21 but also through

10

the sheets 17 and 19.

I provide a resistor strip 27 which is wound through the recesses 23 and across each of the sheets 17 and 19 substantially as shown in Fig. 1 of the drawings. The two heating unit portions 13 and 15 may be held in spaced adjacent positions by relatively thick short strips 29 of electric-insulating material, such as mica, having a thickness of about .035", being positioned against the outer surface of the sheets 19 of aluminum and at each side edge thereof.

15

I provide a hollow metal rivet 31 in the lower portion of part 15, as well as a similar rivet 31 in the lower portion of part 13, to which the ends of the resistor strip may be connected.

20

While I may make the resistor conductor 27 of any of the usual resistance materials, I prefer to use an aluminum resistor and provide the entire outer surface of resistance conductor 27 with an integral, inorganic, heat-conducting, high-temperature-resisting and electric-insulating coating, the thickness of this coating being on the order of .001". While I have mentioned a specific thickness of coating I do not desire to be limited thereto since the thickness of the coating may vary from .0005" to .0015". U. S. Patent No. 1,526,127 discloses one method of making such an electric-insulating coating.

25

The entire outer surface of the sheets 19 of aluminum is also provided with a coating of substantially the same kind as was hereinbefore set forth in connection with resistor conductor 27.

30

Referring now to Fig. 3 of the drawings, I have there shown a modified form of electric heater 33 comprising a single sheet 35 of a suitable electric-insulating material, the thickness of which is substantially the same as was hereinbefore set forth for sheets 17 in Fig. 1, and I provide also a sheet 37 of aluminum. The thickness of the aluminum sheet may be of substantially the same degree as was hereinbefore set forth in connection with sheets 19 of Fig. 1.

35

I provide an insulator strip 39, preferably of mica or the like, which is relatively heavy so that a resistance conductor 41 may be wrapped in recesses 43 in the side strip 39 in the same manner

40

as was hereinabove set forth in connection with the recesses 23, the resistance conductor 41 being adapted to extend across that side of the heating unit upon which the mica sheet 35 is located. Rivets 45 are adapted to hold the parts 35, 37 and 39 in proper operative positions relative to each other.

Referring now to Fig. 4 of the drawings, I have there illustrated a heating unit 47 which is adapted to be provided with a double winding, namely—one in which the resistance conductor extends along both sides of the heating unit. I provide sheets 49 of electric-insulating material, preferably mica, spaced apart by a sheet 51 of aluminum. The sheets 49 are of a thickness on the order of .003" with the same allowable variation as hereinbefore set forth in connection with sheets 17 of Fig. 1, while the thickness of sheet 51 of aluminum is on the order of .035" with substantially the same allowable variation of thickness as was hereinbefore set forth in connection with sheets 19 of Fig. 1.

I provide a pair of strips 53 of electric-insulation, preferably mica, which strip is thick enough (about .035") to receive a plurality of recesses 55 in its outer edge, within which recesses a resistor 57 may be wound to extend across the sheets 49 and 51 from one side to the other and, as has already been set forth, the resistance conductor 57 is adapted to be wound around the heating unit in a substantially helical form.

I have hereinbefore set forth that the thickness of the sheet of electric-insulation is about .003" and while the insulating value of .003" thickness of the electric-insulation is sufficient, its mechanical strength is insufficient to support a resistance conductor 27, 41 or 57, particularly when it is considered that the resistance conductor must be wound upon the very thin sheet of electric-insulation.

In order to provide the sheet of electric-insulation with sufficient mechanical strength to withstand both its handling during the manufacture of the heating unit as well as during the life thereof, I provide a sheet of metal, which sheet of metal is provided over its entire outer surface with an electric-insulating coating, the thickness of which is about .001".

To further ensure a heating unit construction in which the resistance of the sheet of electric-insulation is relied upon mainly to electrically insulate the resistance conductor, I mount the resistance conductor on that side of the assembled sheets of electric-insulation and of aluminum upon which is found the sheet of electric-insulation. The electric-insulating value of the coating on the aluminum sheet is, however, sufficient to withstand breakdown of the electric-insulation sheet and short circuiting of parts of the resistor winding so that I have provided a doubled insulation for the resistor.

The structure shown in Figs. 1 and 2 may be used in the heating units of electric toasters, while the structures shown in Figs. 3 and 4 in-

clusive may be used in any form of electric heater with which the structure embodying my invention may be used.

Various modifications may be made in the device embodying my invention without departing from the spirit and scope thereof and I desire that all such modifications coming clearly within the scope of the appended claims shall be covered thereby.

10 I claim as my invention:

15 1. An electric heating unit comprising a sheet of electric-insulating material too thin to constitute the sole support of an electric resistor, a sheet of metal of light weight and large heat-transmitting characteristics, a relatively thick strip of electric-insulating material secured to said two sheets at each of two opposite edges thereof, recesses in the outer edges of said strips and a resistor member supported by said recesses in said strips extending across the outer surface of said sheet of electric-insulating material.

20 2. An electric heating unit comprising a sheet of electric insulating material too thin to constitute the sole support of an electric resistor, a thin metal backing sheet lying against one surface of said insulating sheet, a relatively thick strip of electric insulating material secured to said two sheets at each of two opposite edges thereof and extending along those edges, said

25 30 35 thick strips extending forward of the surface of said insulating sheet, recesses in the outer edges of said strips, and an elongated resistor strung from strip to strip and lying in said recesses and supported thereby across the outer surface of said insulating sheet and spaced therefrom.

40 45 3. An electric heating unit comprising a sheet of electric insulating material too thin to constitute the sole support of an electric resistor, a thin metal backing sheet lying against one surface of said insulating sheet, a relatively thick spacing strip of electric insulating material lying against the face of said insulating sheet along each of two opposite edges thereof, means for securing said spacing strips to both of said sheets and an elongated resistor strung between said strips and supported thereby spaced from the exposed face of said insulating sheet.

MAX McGRAW.
